UNITED STATES PATENT OFFICE

157,022

PROJECTOR

John T. Armbruster, Niagara Falls, N. Y., assignor
to American Optical Company, Southbridge,
Mass., a voluntary association of Massachusetts

Application January 13, 1949, Serial No. 208

Term of patent 14 years

(Cl. D61—1)

To all whom it may concern:

Be it known that I, John T. Armbruster, a citizen of the United States of America, residing at Niagara Falls, in the county of Niagara and State of New York, have invented a new, original, and ornamental Design for Projectors, of which the following is a specification, reference being made to the accompanying drawings, forming a part thereof.

Fig. 1 is a perspective view of a projector, embodying my new design.

Fig. 2 is a top plan view of same; and

Fig. 3 is a front elevational view of same.

The essential features of my design reside in the parts shown in full lines in the drawing.

I claim:

The ornamental design for a projector, substantially as shown and described.

JOHN T. ARMBRUSTER.
